CLAIM

The ornamental design for a panel light, as shown and described.

DESCRIPTION

FIG. 1 is a front, top left perspective view of a panel light showing my design;

FIG. 2 is a front elevational view of the same;

FIG. 3 is a rear elevational view of the same;

FIG. 4 is a left elevational view of the same;

FIG. 5 is a right elevational view of the same;

FIG. 6 is a top view of the same;

FIG. 7 is a bottom view of the same;

FIG. 8 is a front, top left perspective view of a second embodiment of a panel light showing my design;

FIG. 9 is a front elevational view of the same;

FIG. 10 is a rear elevational view of the same;

FIG. 11 is a left elevational view of the same;

FIG. 12 is a right elevational view of the same;

FIG. 13 is a top view of the same; and,

FIG. 14 is a bottom view of the same.

The broken lines in the drawings illustrate portions of the panel light which forms no part of the claimed design.

1 Claim, 8 Drawing Sheets
